PRESSURE CORE BARREL

Benjamin W. Sewell, Tulsa, Okla., assignor to
Standard Oil Development Company, a corpora-
tion of Delaware

Application April 21, 1939, Serial No. 269,168

19 Claims. (Cl. 255—72)

The present invention is directed to a coring device for securing a core from a substratum under the pressure obtaining in the substratum.

The principal object of the present invention is the provision of a coring device of the character described including a longitudinal retractable barrel for receiving a core and means independent of said barrel for sealing the core under the pressure of the formation from which it was obtained, in which the means for sealing the lower end of the core is operated simply by raising the drill stem.

An additional object of the present invention is the provision of means of the character described in which is provided a valve for sealing off the lower end of the core barrel of such a construction that during the coring operation it is subjected to the flushing action of the drilling fluid.

A further object of the present invention is the provision of a device of the character described including a core barrel and a shell surrounding said barrel and normally fixed for movement therewith in which means are provided for breaking the connection between these elements before the beginning of the coring operation.

Another object of the present invention is the provision of novel means for breaking off a core from the formation from which it is cut.

Further objects and novel features and advantages of the present invention will appear from the following detailed description of the accompanying drawings in which—

Figs. 1, 2 and 3 constitute together a side view, partly in quarter section and partly in half section, of a coring device according to the present invention, said figures being arranged in sequence beginning at the bottom of the coring device;

Fig. 4 is a section of the core barrel along the plane at right angles to the sectional view of Fig. 3;

Fig. 5 is a cross section on the line A—A of Fig. 3;

Fig. 6 is a detailed view of the valve shown in Fig. 1;

Fig. 7 is a cross section along the line B—B of Fig. 1;

Fig. 8 is a cross section along the line C—C of Fig. 1; and

Fig. 9 is a detail view of the core catcher.

Referring to the drawings in detail, numeral 1 designates a conventional core drill head provided with conventional cone cutters 2 and with a central passage 3. The core head is held in threaded engagement with a collar 4, the upper

end of which is in threaded engagement with a cylinder 5, the upper end of which is, in turn, in threaded engagement with a collar 6 slidably mounted on a section 7 of reduced diameter of a nipple 8 carried by a drill stem 9. The inside edge of the bottom end of collar 6 is beveled as at 10 to receive similarly inclined faces of dogs 11, each of which is pivoted on a pin 12 in a longitudinal slot 13 in the wall of section 7. At its free end each of these dogs carries a leaf spring 14, the end of which presses against the inner face of section 7 and normally tends to press the dogs inwardly toward the center of section 7 out of engagement with collar 6.

The inner face of each dog 11 is provided with a ledge 15, the outer edge of which is turned up in the form of a lip 16, said lip being of such configuration as to fit into an annular recess 17 provided on the undersurface of a head 18 carried by sleeve 19 slidably mounted on a rod 20 which is provided at some distance from its end with a shoulder 21 to limit the movement of sleeve 19 at that direction, and is provided with a nut 22 between which and the head 18 is arranged a helical spring 23 which normally forces sleeve 19 against shoulder 21.

The rod 20 is connected at its lower end with a coupling 24 to which is also connected a rod 25 in alignment with rod 20, which carries at its lower end through connections hereinafter described a barrel 26.

The lower end of the barrel 26 rests on a ledge 27 provided on the inner surface of a small tube 28 arranged in passage 3 and threaded to the inner face of the lower end of collar 4. The lower edge of tube 28 is serrated to form cutting teeth in the conventional manner. A plug 29 having a central passage 30 is arranged inside of tube 28 and the lower end of barrel 26, and is connected to the former by a shear pin 31 and to the latter by a shear pin 32. In each case the end of the shear pin which is in the plug is carried by a ring of hard metal which is provided so as to avoid the necessity of making the whole plug of hard metal which might cause some drilling difficulties if the plug should become lost in the hole. Since the barrel 26 and tube 28 are rigidly connected to each other and the latter is rigidly connected to collar 4 and the former to rod 20, it follows that, while pins 31 and 32 are in the position shown, the parts will remain in the relationship shown.

Above the cutting head the collar 4 is provided on its inner face with a shoulder 33 upon which rests a cylindrical valve head 34 which is con-

centric with the barrel 26 and is, in turn, carried by a sleeve 35 which is also concentric with barrel 26. Sleeve 35 is of greater length than barrel 26 and carries at its upper end a cylindrical block 36 which has a central bore 37 through which rod 25 passes. At its lower end, this central passage 37 is enlarged whereby an annular space 38 is formed between its inner face and the rod 25. A radial passage 39 connects space 38 with the exterior of the block. The block is also provided with a laterally offset longitudinal passage 40 controlled by a needle valve 41 and, when open, making connection with a lateral passage 42 provided with a plug 43 for the purpose hereinafter specified. Block 36 is provided with radially extending longitudinal fins 64 which space it from cylinder 5.

Extending upwardly from block 36 is a sleeve 44 concentric with coupling 24, said sleeve normally having a smaller interior diameter than the outside diameter of coupling 24, but being reamed out to form a sliding fit for said coupling for a length defined by shoulders 45 and 46, whereby said coupling is permitted limited longitudinal movement within said sleeve for the purpose hereinafter specified.

At its upper end, sleeve 44 is provided with radially extending longitudinally arranged fins 47 which have inclined upper edges 48 adapted to form a seat for the beveled edge 49 of the inside edge of the lower end of aforesaid section 7. Section 7 is also provided adjacent its lower end with an external inclined shoulder 50 which is adapted to abut against the beveled edge 10 on collar 6 for the purpose of limiting the relative movement of collar 6 and section 7, as hereinafter described.

Rod 25 terminates an appropriately selected distance below the cylindrical block 36 in a collar 51 having a laterally extending upper face upon which is arranged a disk of resilient material 52 which is of such dimension as to form a seat for a knife edge 53 formed on the lower end of annular space 38 in block 36. Screwed into the other end of the collar 51 is a bolt 54, the head 55 of which rests on thrust bearings 56 which are arranged in a cavity provided in the upper end of a cylindrical valve head 57. The bolt 54 is held in place by a screw cap 58 carried by the upper end of the valve head. The valve head is provided around its circumference with slots 59, below which is arranged a seat 60 for a ball valve 61, said seat being held in place by a ring 62. The lower end of the valve head is connected to the barrel 26 by a pin 63.

The valve head 54 is composed of a sleeve 65 which has intermediate its ends a cut-out portion 66. The upper end of the sleeve has internal threads 67 which engage threads on the lower end of sleeve 35, and the remainder of the sleeve has an interior diameter equal to that of sleeve 35 which is slightly larger than the external diameter of barrel 26. The sleeve is provided with diametrically opposed longitudinal ribs 68 which have rounded outer surfaces adapted to slidably engage the interior of cylinder 5. Each rib is provided with a laterally extending shoulder 69 which are adapted to abut against the lower end of cylinder 5, and with a shoulder 70 adapted to abut against shoulder 33 of collar 4. Spaced 90° from the ribs 68 are short ribs 71 which are used for spacing purposes.

Each of the ribs 68 carries a stud 72 pro-

jecting into the space between the ribs. On these studs is journaled a steel ball 73 which is provided with an interior passage 74 for the receipt of barrel 26. Sleeve 65 is suitably recessed just above the cut-away portion 66 to receive a packing ring 75 which is of such configuration as to form a fluid-tight seal with the surface of the ball 73. At either one of its journaled ends ball 73 carries a pinion 76 which is adapted to mesh with a rack 77 carried by the adjacent ribs 68. Each rack is secured to a rib by screws 78 working in slots 79, said rack being laid against the side face of the rib, with its one edge projecting further laterally than the arcuate face of the rib, and is of such a length as to fit between the lower end of cylinder 5 and shoulder 33 on collar 4. Thus, while each rack is secured to a rib which, in turn, is integral with sleeve 65, it acts as though it were secured to collar 4, that is, it is capable of movement relative to sleeve 65 and, therefore, relative to the pinions 76.

As previously stated, a feature of the present invention is the core catcher which is shown in detail in Fig. 9. As can be seen by reference to this figure, the lower end of barrel 26 is provided with a circumferential series of spaced slots 80 and with a second series of these slots 81 spaced from the first series by bars 82. Below the latter series of slots the inner face of the barrel is cut away to form seats 83. In each of these seats is set one end of a flat member 84 of spring steel which is then threaded through the successive slots 81 and 80 around the bar 82 with its free end projecting into the barrel. The arrangement of slots and bars is such that the free end of each flat member is formed into a spring finger normally thrust into the interior of the barrel. The plug 29 is provided with longitudinal recesses 85 to receive these fingers. Likewise, the lower end of the barrel is provided with longitudinal grooves 86 to receive these fingers when a core enters the barrel.

Before describing the operation of this device, a brief recapitulation of the relationship of the parts may be helpful. The core barrel itself is carried by the rod 20 and, until the coring operation begins, by the shear pins 31 and 32, the latter being connected to the barrel and the former being connected to the tube 28 which, in turn, is rigidly connected to collar 4. Collar 4 is rigidly connected to cylinder 5 which, in turn, is rigidly connected to collar 6 which is slidably mounted on reduced section 7 of nipple 8. In order that the rotary movement of drill stem 9 may be transmitted to the collar 6, the latter is provided with a longitudinal key 87 which is seated in a slot 88 in reduced section 7. This slot is of sufficient length to take care of relative longitudinal movement between collar 6 and section 7.

In order to prevent the return of collar 6 to the position shown after the desired longitudinal movement thereof has occurred, reduced section 7 carries dogs 89 which are pivoted on pins 90, mounted in longitudinal slots 91 in section 8 and are spring-pressed outwardly by leaf springs 92. When in their outward position, the dogs are adapted to rest on the top of collar 6 after the latter has been moved downwardly the necessary distance and to prevent the reverse movement of said collar. As will be apparent, the collar 6 is adapted to slide on the reduced section 7, its downward movement being limited by the shoulder 50 on reduced section 7.

The only elements which hold the collar 6 in

the position shown are dogs 11 which, in turn are held in position by the head 18 which, in effect, is carried by the barrel 26 which, in effect, is carried by the collar 6. Accordingly, when the connection between the core barrel and the outer shell, namely the shear pin 31, is broken, the relationships shown in the drawings are automatically changed.

It will be understood that in the use of this device drilling mud must be circulated around the core cutters. This mud flows down inside of the drill stem, down around rod 20 between fins 47, between the fins 64 of the cylindrical valve head 36, between sleeve 35 and cylinder 5 and down outside sleeve 65 to the bottom thereof which is at the top of the drill head which, in turn, is provided with longitudinal passage 93 around its circumference, connecting its upper end with the cutter mountings.

The operation of the core barrel of the present invention is wholly automatic. With the parts in the position shown, the drill stem is lowered to the formation to be cored. When this formation is reached, the weight of the drill stem on the plug 29 first shears pin 31, which causes relative movement between the barrel 26 and the rest of the assembly for the distance permitted by the clearance between collar 24 and shoulder 45. This distance is made just exactly right to permit the head 18 to clear the lip 16 on each dog 11, whereby each lip is forced by its spring 14 into the recess 17 provided in head 18 for that purpose. The spring 23 insures a snug fit between these elements.

Further pressure on the plug 29 shears pins 32 and the coring operation is begun, the plug 29 being pushed up into the barrel by the formation core. As the core moves upwardly into barrel 26, the drilling mud in the latter is forced out through passage 39. When sufficient core has been cut, rotation of the drill stem is stopped and the drill stem is lifted. This causes spring fingers 84 to break off the core at that point. At this time, the only point of the assembly connected directly to the drill stem is the core barrel 26, the rest of the assembly being free for relative movement with respect to the core barrel by reason of the dogs 11 having been pulled inwardly. Thus, with further upward movement of the drill stem the core barrel is drawn upwardly, the rest of the assembly resting on the formation until knife edge 53 comes into contact with its seat 52. At this point, the core barrel has been pulled upwardly a distance sufficient to clear the sleeve 35 to move upwardly, carrying with it sleeve 65. The movement of sleeve 65 relative to collar 4 causes the pinions 16 to run along the racks 71 and rotate the valve 73 sufficient to seal off the lower end of the sleeve 35. At this point the lower edge 10 of the collar 6 has still not abutted against the shoulder 50 on section 7. Further upward pull on the drill stem to make these abutting sections meet, places the spring 23 under compression, thereby tightening the seal between the knife edge and its seal and effectively sealing off the upper end of sleeve 35.

Upon further upward movement of the drill stem, therefore, the entire assembly moves upwardly. When the assembly arrives at the surface, the collar 4 is unscrewed from the cylinder 5, exposing the lower end of sleeve 35. At this time, the dogs 11 are exposed by reason of the collar 6 having slipped down on section 7 and the dogs can be prised out of position by the application of a screw driver or other instrument

to the notch shown at the other end of the dog, or by any other expedient. The release of these dogs makes it then possible to slip out sleeve 35 in its entirety from cylinder 5.

The interior of the sleeve 35 is still under formation pressure. Plug 43 is removed and connection made with suitable sample collecting apparatus. Then needle valve 41 is opened and the pressure on the interior of the sleeve allowed to come down to atmospheric, any volatile constituents contained in the sample passing off to the liquefaction or collecting apparatus for analysis. Upon the release of the interior pressure of the sleeve, the valve 73 can be opened and the rod 25 is disconnected from coupling 24 and the barrel 26 is slipped out of the sleeve.

It will be understood that the device described above simply represents the preferred embodiment of the present invention. Manifestly, a great number of mechanical changes can be made therewith without departing from the scope of the present invention. Instead of the expedients relied upon in the device above described for limiting relative movements of parts, other expedient means can be employed. In short, the present invention is not to be limited by the above description of the accompanying drawings, but only by the appended claims in which it is intended to claim it as broadly as the prior art permits.

I claim:

1. A device for securing a core from a subsurface formation comprising a casing adapted to be connected to a drill stem for rotation therewith, a core barrel carried within said casing capable of longitudinal movement relative thereto and adapted to assume a forward and a retracted position, means for normally holding said barrel in forward position, and means for releasing said last mentioned means at the beginning of the coring operation.

2. A device for securing a core from a subsurface formation comprising a casing adapted to be rotated by a drill stem and capable of longitudinal movement relative thereto, a core barrel carried within said casing capable of longitudinal movement relative thereto and adapted to assume a forward and a retracted position, means for normally holding said barrel in forward position and for holding said casing in fixed longitudinal relation with respect to said drill stem, and means for rendering said last mentioned means inoperative at the beginning of the coring operation.

3. A coring device comprising a casing adapted to be connected to a drill stem for rotation therewith and for longitudinal movement relative thereto, a core barrel carried by said casing, a cutter head carried by said casing having a central passage in alignment with said core barrel, means for normally holding said casing in fixed longitudinal relationship with respect to said drill stem, means for normally holding said barrel in fixed longitudinal relationship with respect to said casing, and means actuated by the impression of the weight of the drill stem upon said casing for disengaging said barrel from said casing, and placing said barrel in fixed longitudinal relationship with respect to said drill stem.

4. A pressure coring device comprising an outer casing, an inner casing concentric with and spaced from said outer casing, a barrel mounted in said inner casing, a cutting head carried by said outer casing having cutters de-

fining a central passage in alignment with said barrel, and means for holding said outer casing, said inner casing and said barrel in fixed longitudinal relationship, with the latter in communication with said central passage, comprising a shear pin adapted to be sheared at the beginning of the coring operation.

5. A device for securing a core from a subsurface formation comprising an outer casing adapted to be connected to a drill stem for rotation therewith, an inner casing concentric with said outer casing and mounted for limited longitudinal movement relative thereto, a core barrel concentric with said inner casing and mounted within said casing for limited longitudinal movement relative thereto, a cutting head carried by said outer casing having cutters defining a central passage in alignment with said core barrel, and a plug mounted in said passage and connected to said outer casing and said core barrel by shear pins and having its end projecting below the cutting head whereby, when the assembly is pressed against the formation to be cored under the weight of the drill stem, said pins are sheared and said barrel is freed for longitudinal movement relative to said outer casing.

6. A device for securing a core from a subsurface formation comprising an outer casing connected to a drill stem for rotation therewith, means for normally holding said casing in fixed longitudinal relationship with said drill stem, an inner casing concentric with said outer casing and mounted for limited longitudinal movement relative thereto, a core barrel carried by said inner casing and mounted for limited longitudinal movement relative thereto, means for normally holding said core barrel in a fixed longitudinal relationship with said outer casing, and means actuated by the weight of the drill stem for disengaging said last mentioned means and simultaneously freeing said outer casing for longitudinal movement with respect to said drill stem and for connecting said barrel to said drill stem for longitudinal movement therewith.

7. A device for securing a core from a subsurface formation comprising an outer casing adapted to be rotated by a drill stem and capable of limited longitudinal movement relative thereto, an inner casing concentric with said outer casing and capable of limited longitudinal movement relative thereto, a barrel mounted within said inner casing and capable of longitudinal movement relative thereto, said barrel being adapted to assume a forward and a retracted position in said inner casing, means carried by said barrel for sealing off the upper end of said inner casing, when said barrel is in its retracted position, a cutting head carried by said casing having cutters defining a central passage in alignment with and in communication with the interior of said barrel, when it is in its forward position, a valve carried by the forward end of said inner casing and located between said cutting head and said barrel when the latter is in its retracted position, means for retracting said barrel after the completion of the coring operation, and means actuated by the retraction of said barrel for closing said valve.

8. A device for securing a core from a subsurface formation comprising an outer casing adapted to be connected to a drill stem for rotation therewith, an inner casing concentric with said outer casing, a core barrel slidably mounted in said inner casing and capable of assuming a forward and a retracted position, a cutting head

carried by said outer casing having cutters defining a central passage in alignment with and in communication with said barrel when it is in its forward position, a valve carried by said inner casing between said head and said barrel when the latter is in its retracted position, means for moving said barrel from its forward position to its retracted position after the completion of the coring operation, and means actuated by the retraction of said barrel for closing said valve.

10. A device for securing a core from a subsurface formation comprising an outer casing adapted to be connected to a drill stem for rotation therewith, an inner casing concentric with said outer casing and mounted for limited longitudinal movement relative thereto, a barrel slidably mounted in said inner casing capable of assuming a forward and a retracted position, a cutter head carried by said outer casing having cutters defining a central passage in alignment with and in communication with said barrel when it is in its forward position, a valve carried by the lower end of said inner casing at a point between said cutter head and said barrel when the latter is in its retracted position, complementary means carried by the upper end of said barrel and the upper end of said inner casing for sealing the upper end of the latter when the barrel is in its retracted position, means for moving said barrel from its forward to its retracted position after the completion of the coring operation, and means actuated by the retraction of said barrel for closing the valve at the lower end of the inner casing.

15. A device for securing a core from a subsurface formation comprising a casing adapted to be connected to a drill stem for rotation therewith and for limited longitudinal movement relative thereto, a core barrel mounted within said casing for longitudinal movement relative to said drill stem, means carried by said drill stem for normally holding said casing in fixed longitudinal relationship with said drill stem, and means actuated by the weight of the drill stem on the assembly for transferring said last mentioned means from the casing to the core barrel, to thereby make said core barrel move longitudinally with said drill stem.

20. A device for securing a core from a subsurface formation comprising an outer casing adapted to be connected to a drill stem for rotation therewith and for limited longitudinal movement relative thereto, means for normally holding said casing in fixed longitudinal relationship with said drill stem, an inner casing concentric with said outer casing and capable of limited longitudinal movement relative thereto, a core barrel mounted within said inner casing for longitudinal movement relative thereto and capable of assuming a forward and a retracted position, a cutter head carried by said outer casing having cutters defining a central passage in alignment and in communication with said barrel when it is in said forward position, a valve carried by the lower end of said inner casing having a central bore for the passage of said core barrel and being adapted to be closed by the retraction of said core barrel into said inner casing, means severable by the weight of the drill stem on said assembly for normally connecting said barrel in forward position to said cutter head, means for imparting longitudinal movement to said barrel relative to said outer casing upon the severance of said connecting means, and means set into operation by said

movement of said barrel for transferring the first mentioned means from said outer casing to said barrel to thereby make said barrel movable longitudinally with said drill stem.

12. A device for securing a core from a subsurface formation comprising an outer casing adapted to be rotated by a drill stem, an inner casing concentric with and spaced from said outer casing for the passage of drilling fluid, a core barrel slidably mounted in said inner casing and adapted to assume a forward and a retracted position, a cutter head carried by said outer casing, having cutters defining a central passage in alignment with and in communication with said barrel when it is in said forward position, a rotatable valve mounted in the lower end of said inner casing at a point between said cutter head and said barrel when the latter is in its retracted position and having a central bore adapted to receive said barrel when it is in its forward position, the walls of said inner casing being cut away adjacent said valve whereby the fluid circulating between said inner casing and said outer casing has access to said valve.

13. A device according to claim 7 including means for holding the core barrel in its retracted position.

14. A device according to claim 8 including means for holding the core barrel in its retracted position.

15. A device according to claim 9 including means for holding the core barrel in its retracted position.

16. A device for securing a core from a subsurface formation comprising an outer casing adapted to be connected to a drill stem for rotation therewith, an inner casing concentric with and spaced from said outer casing and in open fluid communication with said outer casing at both of its ends, a core barrel having an open lower end and being slidably mounted in said inner casing and capable of assuming a forward and a retracted position, a valve at the top of said barrel for permitting the flow of fluid only from said barrel into said inner casing, a cutting head carried by said outer casing having cutters defining a central passage in alignment and in communication with said barrel when it is in its forward position, a valve carried by said inner casing at its lower end between said head and said barrel when the latter is in its retracted position, complementary means carried by the upper end of said barrel and the upper end of said inner casing for sealing the upper end of said inner casing when said barrel is in its retracted position, means for moving said barrel from its forward position to its retracted position after the completion of the coring operation, and

means actuated by the retraction of said barrel for closing the valve at the lower end of said inner casing.

17. A device according to the preceding claim 5 including means for holding said barrel in its retracted position.

18. A device for securing a core from a subsurface formation comprising an outer casing adapted to be connected to a drill stem for rotation therewith, an inner casing concentric with said outer casing and mounted for limited longitudinal movement relative thereto, a core barrel slidably mounted in said inner casing and capable of assuming a forward and a retracted position, a cutting head carried by said outer casing having cutters defining a central passage in alignment and in communication with said barrel when it is in its forward position, a valve carried by said inner casing between said head and said barrel when the latter is in its retracted position, means for moving said barrel from its forward to its retracted position after the completion of the coring operation, cooperating means between said barrel and said inner casing for causing the latter to move with the former after the motion of the former has progressed a predetermined distance, and means set into operation by the movement of said inner casing for closing said valve.

19. A device for securing a core from a subsurface formation comprising an outer casing adapted to be connected to a drill stem for rotation therewith, an inner casing in open fluid communication with and concentric with said casing and mounted for limited longitudinal movement relative thereto, a core barrel slidably mounted in said inner casing and capable of assuming a forward and a retracted position, means carried by said barrel for sealing off the upper end of said inner casing when said barrel is in its retracted position, a cutting head carried by said outer casing having cutters defining a central passage in alignment and in communication with said barrel when it is in its forward position, a valve carried by said inner casing between said head and said barrel when the latter is in its retracted position, means for moving said barrel from its forward position to its retracted position after the completion of the coring operation, whereby the upper end of said inner casing is sealed off and further upward movement of said barrel causes said inner casing to move upwardly relative to said outer casing, and means operatively associated with said inner casing and said outer casing for closing said valve upon relative longitudinal motion between said casings.

BENJAMIN W. SEWELL.
